UNITED STATES PATENT OFFICE

WALTER J. FRINK, OF CHATTANOOGA, TENNESSEE

HOBBY HORSE

Application filed December 26, 1929. Serial No. 416,649.

This invention relates to toys and particularly toys in the nature of hobby horses.

An object of the invention is to provide a toy which in operation will simulate a horse so that a child may ride with substantially all of the movements, benefits and thrills gained from actual horse back riding.

Another object of the invention is to provide mechanism operable by a child for propelling the toy horse forward by simply raising and lowering himself from the seat in the manner in which a person would in actually riding horse back. By raising himself off the seat certain spring mechanism operates to move the rear portion of the horse forward and this portion is locked in its forward position as the rider puts his weight upon the seat to move the front feet of the horse forward, the body of the horse pivoting on the rear legs in order to prevent rear movement of the horse instead of forward movement as the rider seats himself in the saddle.

A further object is to provide in a toy of this character certain novel features of construction in detail of the hobby horse.

Referring to the accompanying drawings, which are made a part hereof and on which similar reference characters indicate similar parts,

Figure 1 is a view in elevation of the invention,

Figure 2, a view as seen from the rear in Figure 1,

Figure 3, a partial sectional view taken on line 3-3 of Figure 2,

Figure 4, a detail of a modified form,

Figure 5, a further modified detail, and

Figure 6, a detail view of the connection between the leg and the seat as shown in modified forms in Figures 4 and 5.

In the drawings numerals 10 and 11 indicate front and rear wheels respectively on which the horse is mounted. A front upright piece 12 is bifurcated on its lower end to straddle the front wheel 10 and is pivotally mounted on an axle pin 13 on the front wheel. This front portion is cut to resemble such outline of a horse's head, neck and shoulders as will make an attractive de-

sign. Near the upper forward portion of the head member is attached a clip 14 which may be and preferably is made of metal and is bent over and pivoted at 15 to what might be termed the forehead of the horse and bent around to fit against opposite sides of the horse's head. This clip is preferably slotted to something near its mid-portion as indicated at 16. The portion 14 is designed to represent the horse's ears and when laid back in the position shown in Figure 1 the upper edge of the slot at 16 will rest against the upper straight portion of the neck of the horse. Suitable conventional or artistic designs such as 17 and 18 may denote the horse's eye and nose. A short transverse bar 19 is secured at the upper neck portion to provide a grip for the child by means of which he may hold himself upon and guide the horse. Secured to the rear of the front portion 12 is a bracket 20 which has its ends bent out as shown at 21 to receive an upright block 22 which is pivotally secured within the bracket by means of a bolt 23. A flat body portion 24 is rigidly secured at its front end to the post 22. The post 22 likewise has a depending end 25 which supports stirrups 26. The stirrups 26 are preferably pivoted on a pin 27 which extends sufficiently far out to provide a rest for a child's foot. In order to simulate a stirrup a small strap 28 may be attached to the upper end of the stirrups. A saddle 30 is pivoted at 31 to the rear of the post 22. This saddle is supported near its central point on a spring 32 which rests upon and near the center of the body member 24. The spring 32 may be placed closer or further from the pivot point of the saddle depending on whether the horse is for a light or heavy rider. If desirable the spring may be seated so as to be adjustable forward or backwards. Rear legs 33 and 34 are hinged at 35 to the under side of the saddle. The lower ends of the legs are pivotally mounted on an axle 41. Any suitable form of wheel may be used but I have found those which resemble a disk with a leather or rubber tire to simulate rubber tires most attractive and satisfactory. It is desirable particularly to have a rear tire with con-

siderable co-efficient of friction for a purpose which will later appear.

The inside of the rear legs and just above the joint is dished out to provide an arcuate ledge as shown at 42 and a bar 43 has its ends resting on the ledge provided by this dished out portion. The bar is secured cross-wise of the end of the body portion 24. A strengthening and supporting bar 44 is secured to the inner edge of each of the rear legs. This provides a strong brace for supporting the rear legs. A block 45 secured to the underside of the body portion 24 together with bar 44 limits forward movement of the rear legs as the bar 44 strikes the rear end of this block. A brake bar 46 is pivoted at 47 to one of the rear legs. This brake bar has its lower end split and one portion 29 of this split part is bent over and across the edge of the wheel so as to engage the tire of the wheel and serve as a brake. The other portion 36 of the split end is bent in the other direction and is perforated to receive loosely the lower end of a rod 48. This rod is pivoted at 49 to the rear of the saddle and passes through and fulcrums in an eye 50 on the leg of the horse. The lower end of the rod 48 may have a nut thereon or be bent over to prevent the end of a brake bar from dropping off. A strap 51 secured to the rear of the saddle may indicate the horse's tail. Likewise a strap 52 secured in rings 53 at the portion which indicates the horse's mouth may provide a bridle. The head of the horse may be lined or marked as shown at 54 to indicate further elements of the bridle, or, if preferred, actual leather straps may be secured to the horse's neck and head along these portions to indicate a complete bridle.

The operation of the device is as follows: When at rest the horse stands in the position shown in full lines in Figure 1. When in this position the brake bar 46 is supported on the end of the rod 48 and the braking end is held out of contact with the wheel. Assume that a child mounts the horse and starts to ride; he first places his feet on the stirrups 27 and raises himself; he then lowers himself on the seat and his weight presses the seat down to the upper ends of the rear legs which legs pivot on the rear axle 41. As the saddle is moved downward the rod 48 slides down and allows the brake bar to engage the rear wheel and prevents the wheel from rotating backwards. In order for the hind legs to pivot on the axle 41 they must push the front wheel forward to move the horse forward to the position shown in dotted lines 55. The child then swings his weight forward and supports himself on the pin 27. This throws his weight nearer to the front of the horse and places the load on the front wheel. As he rises up the spring 32 lifts the saddle and swings the rear legs back to

the full line position shown in Figure 1. The rear legs pivot this time at 35 and the rear wheels are brought forward to assume the position shown in full lines in Figure 1. These actions are repeated and the horse moves forward step-by-step with the child raising and lowering himself on the saddle as if on a trotting or galloping horse.

Instead of having the body member 24 secured to a transverse bar 43 and having the transverse bar slidably mounted on ledges as shown I may have a bar 24', as shown in Figure 4, mounted to slide upon a transverse bar 56 which is secured to the inner sides of the legs one of which is indicated by the numeral 34'. This bar 56 may, and preferably does, have a roller 57 upon which the rear end of the bar 24' rests to eliminate friction and the front end of the bar 24' is rigidly secured to a post not shown in this figure but substantially as that shown in Figure 1 at 22. In a still further modification, Fig. 5, which is substantially the same as shown in Fig. 4, instead of the bar 56 and roller 57, I substitute a flat bar 58 on which the body member 24'' is slidably resting. The leg 34'' is pivotally connected to the seat 30''. These forms are somewhat simpler than that shown in the preferred form.

While I have shown my toy in the form of a horse because the horse is the beast of burden best known in this country, obviously I do not limit myself to this specific type of animal as the same mechanism could well adapt itself to any other animal without departing at all from the spirit of the invention.

While the device has been referred to as a toy this term is not to be regarded as limiting the use of the device in any sense. It may be used as an exercising device and when made in large size is well adapted for use in the gymnasium for such purpose.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. A hobby horse comprising front and rear wheels, front and rear legs mounted on the wheels, a body portion pivoted to the front legs and a saddle pivoted to the body portion and to the rear legs and adapted upon rocking motion to swing the rear legs on their pivots, substantially as set forth.
2. A hobby horse comprising a front body member composed of head and legs supported on the axle of a front wheel, a central body portion pivoted to the front body portion, a pair of rear legs mounted upon rear

wheels, a saddle pivoted to the central body portion and to the tops of the legs whereby rocking of the saddle on its pivot will swing the rear legs on their pivots, substantially as set forth.

3. A hobby horse comprising a front body member composed of head and legs supported on the axle of a front wheel, a central body portion pivoted to the front body portion, a pair of rear legs pivotally mounted upon rear wheels, a saddle pivoted to the central body portion and to the tops of the legs whereby rocking of the saddle on its pivot will swing the rear legs on their pivots, and a bar pivoted to one of the legs and adapted to engage one of the wheels to act as a brake, substantially as set forth.

4. A hobby horse comprising a pair of rear wheels and a front wheel, a pair of rear legs mounted upon the rear wheels and a pair of front legs supported on the front wheel, front and central body portions, a saddle pivoted to the central body portion and to the tops of the rear legs so that swinging of the saddle on its pivot will rock the rear legs on their pivots and means for preventing the rear movement of the rear wheels as the saddle is rocked on its pivot whereby said rocking will move the front wheels forward, substantially as set forth.

5. A hobby horse comprising a body, a pair of rear wheels and a front wheel, a pair of rear legs mounted on the rear wheels and pivoted to swing forward of the body of the horse, and a bar pivoted to one of the legs operable by the rider for locking the wheels to prevent rear movement of the horse and so as to move the front portion of the horse forward, substantially as set forth.

6. A hobby horse having a body provided with a saddle pivoted thereto, front legs pivoted to said body, and rear legs pivoted to said saddle at its free end, said legs being mounted upon wheels, the said saddle being operable by the rider for swinging the rear legs on their pivots to move the front of the horse forward, and means connected to said saddle simultaneously operable to lock the rear wheels to prevent their moving to the rear as the front portion of the horse is moved forward, substantially as set forth.

In witness whereof, I have hereunto set my hand at Chattanooga, Tennessee, this nineteenth day of December, A. D. nineteen hundred and twenty-nine.

WALTER J. FRINK.
